Primary Examiner — Eric L Goodman*Assistant Examiner* — Daniel J Domino(74) *Attorney, Agent, or Firm* — Finnegan, Henderson, Farabow, Garrett & Dunner LLP(57) **CLAIM**

The ornamental design for a display screen with animated graphical user interface, as shown and described.

DESCRIPTION

FIG. 1 is a first image in a sequence of a front elevation view of a display screen with animated graphical user interface, showing the new design;

FIG. 2 is a second image thereof;

FIG. 3 is a third image thereof;

FIG. 4 is a fourth image thereof;

FIG. 5 is a fifth image thereof;

FIG. 6 is a sixth image thereof; and,

FIG. 7 is a seventh image thereof.

The appearance of the images transition sequentially between the images shown in FIGS. 1-7. The process or period in which one image transitions to another forms no part of the claimed design.

The broken lines of uneven length show the display screen and form no part of the claimed design.
